Filed June 5, 1959, Ser. No. 818,435
1 Claim. (Cl. 179—90)

This invention relates to telephone dials and is more particularly directed to an improvement therein.

The main object of this invention is to minimize the friction, disagreeable feeling and fatigue followed by rotation produced between the finger tip and finger hole when the dial finger wheel is rotated.

It is an another important object of the invention that the finger wheel works accurately and can easily be attached to known telephone dials with a low production cost.

In the accompanying drawing:

FIG. 1 is a top plan view of a finger wheel in accordance with the present invention.

FIG. 2 is an enlarged cross-sectional view of a finger opening portion of the finger wheel with a ring insert.

And FIG. 3 is a top view partly broken away of the ring insert on the finger wheel.

The present invention consists of a ring insert 3 freely and rotatably arranged along the inner circumference of the finger opening 1 of the telephone dial finger wheel 2 provided with any number of finger openings.

Each annular finger opening 1 has a series of small spaced apart protrusions 4 of equal length and with convex ends extending inwardly and radially of and around said opening providing an annular interrupted bearing surface defining the side of said opening.

Each ring insert 3 has a concave outer periphery 5 slideably embracing said protrusions 4 and overlapping the adjacent portion of said finger wheel while the inner periphery 6 is convex. In use the telephone dial finger wheel 2 is rotated by pushing the ring insert 3 with the finger tip, whereby ring 3 rotates freely within the finger

2

opening 1 and the finger tip moves with the ring 3, so that the friction, disagreeable feeling and fatigue followed by rotation produced between the finger tip and finger opening can be eliminated. Particularly with the 5 dial finger wheel 2 and the ring insert 3 are kept in point contact along the interrupted small ridges 4, rotational relation between both of them is carried out very smoothly, and thus the main object of this invention can be achieved more effectively.

Moreover, as the rotating ring insert 3 envelopes the circumferential wall of the finger opening 1, the dial finger wheel 2 can be rotated easily and lightly with no need of full insertion of finger tip into the ring insert and it is very convenient for the dial operators who must rotate the telephone dial frequently.

What I claim is:

An improvement in telephone dials comprising a rotatably mounted finger wheel having at least one opening therethrough, said finger wheel having a series of spaced 20 apart protrusions of equal length with convex ends extending inwardly and radially of and around said finger wheel opening providing an annular interrupted bearing surface defining the side of said opening, a ring shaped insert having a concave periphery with said protrusions 25 extending completely therein slideably supporting said insert for rotation therearound with said ring shaped insert periphery slideably abutting said bearing surface when being used and said ring shaped insert having a central opening with a convex wall defining said opening for 30 receiving the finger of a person for rotating said finger wheel.
